UNITED STATES PATENT OFFICE.

GUSTAV PLOGER, OF DELL, MONTANA.

AEROPLANE.

Application filed December 5, 1928. Serial No. 323,846.

The present invention relates to certain new and useful improvements in aeroplanes and has particular reference to propelling means therefor. This invention constitutes an improvement in the construction disclosed in my prior United States Letters Patent No. 1,659,744 and has particular reference to the air pockets formed in the machine for receiving the propelling force of the propeller blades in a manner for exerting a lifting force upon the machine, the invention having for its principal object to provide a series of louvers at each side of the pocket in association with the respective propellers whereby to reduce the lifting efforts required.

A still further object is to provide a telescoping air pipe for discharging the air from the air pockets against the rudder of the machine and arranged through its telescoping adjustment to control the volume of air delivered against the rudder.

Other objects and advantages reside in the special construction, combination and arrangement of the various elements forming the invention as more fully hereinafter described and claimed, reference being had to the accompanying drawings forming part hereof, wherein like numerals refer to like parts throughout, and in which:

Figure 1 is a side elevational view with parts broken away and shown in section,

Figure 2 is a similar view illustrating the air pipe in its extreme open position,

Figure 3 is a top plan view,

Figure 4 is a vertical transverse sectional view,

Figure 5 is a sectional view through the air pocket taken along a line 5-5 of Figure 4.

Figure 6 is a front elevational view of the casing forming the air pocket, and

Figure 7 is a vertical sectional view therethrough taken along a line 7-7 of Figure 4.

Referring now to the accompanying drawings wherein for the purpose of illustration I have disclosed a preferred embodiment of my invention, the numeral 5 designates a fuselage of the machine mounted on a suitable landing 6 with the upward forward portion thereof provided with a cockpit 7 within which is arranged the control mechanism for the various elements of the machine.

The rear end of the fuselage is provided

with the usual vertically pivoted rough rudder 8 for the direction of control of the machine and the horizontally disposed tail plane 9 providing means for the elevational control thereof.

The rudders and tail planes may be controlled in any conventional manner from the cockpit, such control means not constituting a part of my invention and accordingly are not shown in the present disclosure thereof. The underside of the fuselage intermediate its ends is open to provide an air space within the same, the limitations of said air space at the rear being indicated by the rearwardly inclined wall 10 and with the forward end of said air space terminating rearward of the cockpit.

Within this air space is arranged a horizontal transversely disposed side shaft 11 having each end suitably supported in bearings 12 arranged at the opposite sides of the fuselage head adjacent each end of the shaft, inwardly of the bearings, is rotatably mounted a wheel member 13, adapted for the free rotary movement upon the shaft.

Each side of the fuselage, immediately adjacent each of the wheels is open as clearly indicated at 14. The wheels at the opposite ends of the shaft form the ends of a substantially cylindrical casing 15 having its lower side open as shown at 16.

The shaft 11 is axially disposed with respect to the casing 15, said shaft being operated through the motor 17 supported intermediate the ends of the shaft and is utilized to drive a pair of propeller blades 18 mounted adjacent the ends of the shaft inwardly of the wheels 13, as clearly illustrated in Figure 4 of the drawings.

A double set of louvers 19 are arranged within the casing and disposed adjacent the respective ends thereof, said louvers being arranged in uniformly spaced relation with respect to each other and arranged transversely of the casing with the opposite ends of the louvers attached to the inner walls of the casing in any suitable manner as for instance by spot welding or the like as indicated at 20. The upper and lower edges of the louvers are disposed at a substantially horizontal plane, when the casing is arranged in a normal position, the lower ends of each of the louvers shown at 21 being inclined inwardly and downwardly in an arc and each set of the louvers at the respective

ends of the casing are arranged with each succeeding uppermost louver member stepped inwardly from the adjacent end of the casing in a regular order so that the 5 uppermost louver of each set is disposed adjacent the center of the casing.

An opening is formed in the rear wall 10 of the open face of the fuselage, through which is inserted the forward section 22 of 10 an air pipe, the rear end of said pipe being telescopically arranged in a rear air pipe section 23 having its rear end open and disposed immediately forwardly of the rudder 8.

15 The upper portion of the forward pipe section 22 is open and shown at 24. An operating rod 25 for the forward pipe section 22 is attached at its rear end to said pipe section with its forward end disposed 20 in the cockpit for operation by the aviator.

Through the forward and rearward movement of the rod 25, the forward end of the pipe section 22 may be moved so as to extend inwardly of the lower edge of the opening 16 of the casing so as to admit the air from the casing into the pipe for discharging against the rudder 8. To the hub of each of the wheels 13 is attached a lever 26 having connection to a forwardly extending rod 27 with a control lever 28 arranged in association with a quadrant 29 mounted in the cockpit whereby to provide for the manual limited rotary movement of the casing upon the shaft 11 whereby to 35 move the louvers into a forwardly or rearwardly inclined position. The wings 30 of the plane are attached at their inner ends at the sides of the fuselage at a substantially horizontal plane with the shaft 11 so that the force of air entering the openings at 40 the sides of the fuselage will have an equal effect upon both the upper and lower surfaces of the wing.

It will be apparent from the foregoing 45 that the force of air entering the opposite ends of the casing through the action of the propellers 18 will be directed against the louvers 19, which, by reason of their inclined position, will cause air to exert a lifting force upon the machine.

50 By adjusting the angle of the louvers through the manipulation of the lever 28, this lifting force may be controlled so as to cause the air to drive the machine forwardly or to retard the forward movement thereof, as desired.

When the machine is being driven at a substantially horizontal plane the air from the casing 15 may be discharged through the pipe sections 22 and 23 against the rudder 8 and tail planes 9 thereby aiding the stabilization of the machine.

It is obvious that my invention is susceptible to various changes and modifications in construction without departing from the spirit of the invention or the scope of the

appended claims, and I accordingly claim all such forms of the device to which I am entitled.

Having thus described my invention, what I claim as new is:

1. In combination, an aeroplane including a fuselage, directional and elevational control means at the rear end of said fuselage, a shaft extending transversely of the fuselage, propellers mounted adjacent each end of said shaft, an open ended casing mounted for free rotary movement upon the shaft, said fuselage having openings formed in its side and lower portions immediately adjacent said casing, said casing having one side open and communicating with the open portion at the bottom of the fuselage, manual control means for the casing and a double set of louvers arranged respectively adjacent the ends of the casing and arranged in position for receiving the force of air from said propellers. 70

2. In combination, an aeroplane including a fuselage, directional and elevational control means at the rear end of said fuselage, a shaft extending transversely of the fuselage, propellers mounted adjacent each end of said shaft, an open ended casing mounted for free rotary movement upon the shaft, said fuselage having openings formed in its side and lower portions immediately adjacent said casing, said casing having one side open and communicating with the open portion at the bottom of the fuselage, manual control means for the casing and a double set of louvers arranged respectively adjacent the ends of the casing and arranged in position for receiving the force of air from said propellers, said louvers having their upper and lower edges disposed at a substantially horizontal plane with the louvers of each set disposed in spaced relation and in overlapping position and also arranged with each succeeding upper louver stepped inwardly. 95

100 3. In combination, an aeroplane including a fuselage, directional and elevational control means at the rear end of said fuselage, a shaft extending transversely of the fuselage, propellers mounted adjacent each end of said shaft, an open ended casing mounted for free rotary movement upon the shaft, said fuselage having openings formed in its side and lower portions immediately adjacent said casing, said casing having one side open and communicating with the open portion at the bottom of the fuselage, manual control means for the casing and a double set of louvers arranged respectively adjacent the ends of the casing and arranged in position for receiving the force of air from said propellers, said louvers having their upper and lower edges disposed at a substantially horizontal plane with the louvers of each set disposed in spaced relation and 105 110 115 120 125 130

in overlapping position and also arranged with each succeeding upper louver stepped inwardly, each set of louvers being adjustable as a unit through the manipulation of 5 the casing adjusting means for selectively positioning the lower edges of the louvers in a forwardly or rearwardly inclined position.

4. In combination, an aeroplane including a fuselage, directional and elevational control means at the rear end of said fuselage, a shaft extending transversely of the fuselage, propellers mounted adjacent each end of said shaft, an open ended casing mounted for free rotary movement upon the shaft, 10 said fuselage having openings formed in its side and lower portions immediately adjacent said casing, said casing having one side open and communicating with the open portion at the bottom of the fuselage, manual control means for the casing and a double set of louvers arranged respectively adjacent the ends of the casing and arranged 15 in position for receiving the force of air from said propellers, said louvers having

their upper and lower edges disposed at a 25 substantially horizontal plane with the louvers of each set disposed in spaced relation and in overlapping position and also arranged with each succeeding upper louver stepped inwardly, each set of louvers being 30 adjustable as a unit through the manipulation of the casing adjusting means for selectively positioning the lower edges of the louvers in a forwardly or rearwardly inclined position, and a pair of telescoping 35 air pipes extended longitudinally of the fuselage at the rear end thereof with the rear end of the pipe open and terminating in a position immediately forwardly of the rudder, said pipe having its forward extension open at its upper side and manually operable means for moving the forward end of the pipe into and out of the open side of 40 casing for discharging air from the casing to said pipe. 45

In testimony whereof I affix my signature.

GUSTAV PLOGER.
